UNITED STATES PATENT OFFICE

RALPH C. BEVANS, OF NORTH QUINCY, MASSACHUSETTS

WINDOW SCREEN MOUNTING

Application filed November 17, 1932. Serial No. 643,081.

This invention relates to window screen mountings and has for its object the provision of simple but effective means whereby the screen will always be centered in the window frame on guides which are permanently attached to the outer bead of said frame, the screen being provided with locking means coacting with said guides under normal conditions and which may be quickly detached from said guides to permit the removal of the screen.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings

Figure 1 represents a horizontal section through a window frame provided with screen guides embodying a part of the present invention.

Figure 2 represents a front elevation of said window frame with a screen mounted therein and provided with locking means coacting with the guides of said window frame, said screen with its locking means forming another part of said invention.

Figure 3 represents a horizontal section of a portion of a window frame and showing a screen mounted therein, the cutting plane being on line 3,3, on Fig. 2.

Figure 4 represents a vertical section on line 4,4, on Fig. 3.

Figure 5 represents an end elevation of a portion of the screen and the end of one of the locking devices mounted thereon.

Figure 6 represents an elevation of a portion of one of the screen guide members.

Figure 7 represents a plan of one of the locking bolts.

Figure 8 represents an elevation of one of the locking bolt casings.

Figure 9 is a sectional view similar to Fig. 3 showing the locking device without the removable finger grip.

Similar characters indicate like parts throughout the several figures of the drawings.

In the drawings, 10 is a window casing of usual construction provided at the rear end with vertical side beads 11 between which and the parting beads 12 the upper window sash is adapted to move.

To the oppositely disposed faces of the side beads 11 are secured U-shaped guide members 13 preferably made of sheet metal bent to form flanges 14,14 α extending toward each other, as shown in Figs. 1 and 3 of the drawings.

The rear flange 14 α extends inwardly a distance considerably less than the inward extension of the flange 14.

The window screen frame 15 has side extensions 16 formed at the rear of the vertical side bars 17 of said frame 15 and extending the entire length thereof, the inner faces of said extensions 16 being separated from the rear faces of the flanges 14 α of said metal guide members 13.

The side faces of these extensions 16 are separated from the bead 11 a distance slightly greater than the depth of the flanges 14 α .

The side bars 17 of the screen frame 15 have embedded therein housings or casings 18, each having a slideable locking bolt 19 mounted therein.

Each bolt 19 has at its outer end a flattened portion 20, the rear face of which is aligned with the front faces of the flanges 14 α and is adapted to be moved outwardly to coact with a flange 14 α .

When the portions 20 are coacting with the flanges 14 α the front faces of the screen 15 are bearing against the rear faces of the flanges 14, as shown in the drawings.

The flattened portions 20 are preferably formed integral with the cylinder 21 movable endwise in the housings or casings 18 and each cylinder 21 is provided with a shank 22 to the outer end of which is threaded a head

23 by which the cylinder may be moved endwise against the tension of a spring 24 within the casing 18.

5 The flattened portions 20 are always retained in vertical position by ribs 25 on the casings 18 extending into grooves 26 formed in the cylinders 21 and the casings 18 are prevented from turning about their axes by the fins 27 extending into the wood of side 10 bars 17.

The inner ends of the casings 18 are provided with tubular projections 28 forming bearings for the shanks 22.

15 The guide member 13 is finished or colored like the bead 11 to which it is secured so that when one of the window sashes is moved from its normal position the guide member 13 will not be noticed.

20 When the window is closed the window sashes will hide the guide members 13 from view.

The locking bolts 19 need be provided with heads 23 only at one side of the screen frame 15, while the opposite bolts may be made 25 headless, as shown in Fig. 9.

20 The heads 23 on the bolts 19 may be made of any desired shape provided they contain surfaces which may be gripped by the fingers when the bolts 19 are to be withdrawn.

25 While one means is shown whereby the flattened portions 20 are retained in vertical position, it is obvious other means may be employed to obtain the same result.

30 As shown in Fig. 2 the screen frame 13 is narrower than the window casing, making it possible to adapt the screen frame to window casings of varying widths or to window casings slightly warped.

35 Sometimes these window casings are to some extent out of true, that is, their sides are not exactly parallel, but even in these cases the screen frame 15 may be fitted readily thereto.

40 There is always a space between the window casing 10 and the outer side edges of the extensions 16 projecting laterally from the bars 17 of the screen frame 15 so that this frame 15 may be moved sidewise to some extent.

45 When the frame 15 is mounted on the guide members 13 the springs 24 in the locking devices will center the same in the window casing.

50 If it is desired to remove the screen frame 15 from the window casing, said frame is moved to the left, as seen in Fig. 2, until the outer edges of side extensions 16 of bars 17 are in contact with the bead 11, the springs 24 in the locking devices at the left of the frame 15 being compressed during this movement.

55 The bolts 19 of the locking devices on the right hand bars are then moved to the left disengaging the flattened portions 20 from the flange 14a, and as soon as this disen-

gagement has been effected the right side of frame 15 is moved outwardly beyond the window casing and the frame may then be disengaged from the guide member 13 on the left side of the window casing.

70 By a reversal of these movements the screen frame 15 may be mounted again on the guide members 13.

75 It is the intention to have the manufacturers of the window casings furnish said casings to the builders with the metal guide members 13 mounted thereon to be installed in the building during its construction, and then when the screens are to be supplied no accurate measurements will be required for the reason that knowing the general width of the window casing screens for substantially that width may be forwarded and quickly installed.

80 This is of great advantage as screen frames may be made in quantities and supplied of the general width of any size window and installed quickly, thus saving the labor of men going to the building, taking accurate measurements of the casings, and then constructing the screen frames in accordance with the measurement of each particular window.

85 It is believed that the operation and many advantages of the invention will be understood without further description.

90 Having thus described my invention, I claim:

1. In a screen frame mounting consisting of two U-shaped guide members having front and rear flanges and adapted to project from the outer sash beads of a window casing; a screen frame slidable with its front face contacting with the front flanges of said guide members; and locking devices on the side bars of said frame adapted to coact with said rear flanges.

100 2. In a screen frame mounting consisting of two U-shaped metal guide members and adapted to project from the outer sash beads of a window casing; a slidable screen frame having side extensions in the rear of said guide members, and locking devices on the side bars of said frame adapted to bear against the inner faces of the rear flanges of said guide members and retain the front face of said screen in contact with the front flanges.

110 3. In a screen frame mounting consisting of two U-shaped guide members and adapted to project from the outer sash beads of a window casing and of which the rear flanges have a depth less than that of the front flanges; a screen frame, said frame being slidable with its front face in contact with the front flanges of said guide members; and spring actuated locking devices on the side bars of said frame adapted to bear against the inner faces of said rear flanges.

120 4. In a screen frame mounting consisting

of two U-shaped guide members and adapted to project from the outer sash beads of a window casing and of which the rear flanges have a depth less than that of the front flanges; a screen frame, said frame being slidable with its front face in contact with the front flanges of said guide members; spring actuated locking devices on the side bars of said frame adapted to bear against the inner faces of said rear flanges; and means for releasing said locking devices from contact with said rear flanges.

5. In a screen frame mounting consisting of two U-shaped guide members and adapted to project from the outer sash beads of a window casing and of which the rear flanges have a depth less than that of the front flanges; a screen frame, said frame being slidable in contact with the front flanges of said guide members; and locking devices embedded in the side bars of said frame adapted to bear against the inner faces of said rear flanges.

6. In a screen frame mounting consisting of a U-shaped metal member adapted to project from the outer sash guide bead of a window casing and adapted to serve as guide for a screen frame provided with a laterally movable bolt having a flattened portion adapted to contact with the front face of the rear flange of said guide member.

7. In a screen frame mounting consisting of a U-shaped guide member having front and rear flanges and adapted to project from the outer sash guide bead of a window casing; a screen frame slidable in contact with the front flanges; a non-rotatable housing embedded in a side bar of said frame; and a non-rotatable slidable bolt in said housing provided with a flattened end adapted to contact with the inner face of a rear flange.

8. In a screen frame mounting consisting of a U-shaped guide member having front and rear flanges and adapted to project from the outer sash guide bead of a window casing; a screen frame slidable in contact with the front flange; non-rotatable housings embedded in a side bar of said frame; a slidable bolt in said housing provided with means coacting with the rear flange of said guide member; and a spring for forcing said bolt into coacting engagement with said rear flange.

9. In a screen frame mounting consisting of a U-shaped guide member having front and rear flanges and adapted to project from the outer sash guide bead of a window casing; a screen frame having a side extension in the rear of said guide member and slideable in contact with the front flange; and a locking device on a side bar of said frame adapted to engage the front face of said rear flange.

10. In a screen frame mounting consisting of a U-shaped metal guide member having

front and rear flanges and adapted to project from the outer sash guide bead of a window casing; a screen frame slidable in contact with the front flange of said guide member; and movable means on a side bar of said frame adapted to engage the front face of said rear flange.

11. In a screen frame mounting consisting of a U-shaped guide member having front and rear flanges and adapted to project from the outer sash guide bead of a window casing; a screen frame slidable in contact with the front flange of said guide member; and a spring actuated member on a side bar of said frame adapted to engage the front face of said rear flange.

12. In a screen frame mounting consisting of a U-shaped guide member having front and rear flanges and adapted to project from the outer sash guide bead of a window casing; a screen frame slidable in contact with the front flange and having a side extension in the rear of said guide member; and a slidable member on a side bar of said frame adapted to engage the front face of said rear flange.

13. In a screen frame mounting consisting of a U-shaped guide member having front and rear flanges and adapted to project from the outer sash guide bead of a window casing; a screen frame slidable in contact with the front flange; and slidable bolt extending through a side bar of said frame having flattened portions adapted to engage the front face of said rear flange.

14. In a screen frame mounting consisting of two oppositely disposed U-shaped guide members adapted to project from the rear sash beads of a window casing and having front and rear flanges; a screen frame slideable in contact with the oppositely disposed front flanges; and means on said frame coacting with the front faces of said rear flanges normally retaining said frame in contact with the rear faces of said front flanges.

15. In a screen frame mounting consisting of two oppositely disposed vertical guide members adapted to project from the rear sash beads of a window casing and having front and rear flanges extending toward each other; a screen frame slideable in contact with the oppositely disposed front flanges; and slidable bolts on said frame having flattened portions coacting with said rear flanges to retain said frame in contact with the rear faces of said front flanges.

16. In a screen frame mounting consisting of two oppositely disposed vertical guide members adapted to project from the rear sash beads of a window casing and having front and rear flanges extending toward each other; a screen frame having side extensions in the rear of said guide members; and spring actuated slideable members on said frame coacting with said rear flanges to re-

tain said frame in contact with the rear faces of said front flanges.

17. In a screen frame mounting consisting of two oppositely disposed vertical guide members adapted to project from the rear sash beads of a window casing and having front and rear flanges extending toward each other; a screen frame having side extensions in the rear of said guide members; slidable members embedded in the side bars of said frame coacting with said rear flanges to retain said frame in contact with the rear faces of said front flanges; and means whereby said slidable means may be disengaged from said rear flanges.

Signed by me at 294 Washington St., Boston, Mass., this 31st day of October, 1932.

RALPH C. BEVANS.
